UNITED STATES PATENT OFFICE.

JOHN PEDDER AND GEORGE ABEL, OF WEST PITTSBURG, PENNSYLVANIA.

IMPROVEMENT IN DIES FOR FORGING HARROW-TEETH.

Specification forming part of Letters Patent No. 124,619, dated March 12, 1872.

SPECIFICATION.

To all whom it may concern:

Be it known that we, JOHN PEDDER and GEORGE ABEL, of West Pittsburg, in the county of Allegheny and State of Pennsylvania, have invented a new and useful Improvement in Dies for Forming Pointed Blanks; and we do hereby declare the following to be a full, clear, and exact description thereof, reference being had to the accompanying drawings making a part of this specification, in which—

Figure 1 is a side elevation of our machine. Fig. 2 is a top or end view (enlarged) of the swaging-dies of Fig. 1. Fig. 3 shows in perspective the form of die suitable for pointing round iron by swaging. Fig. 4 shows in perspective one of a pair of dies, having a series of faces to be used successively in the work of pointing. Fig. 5 is an enlarged end view through x x , Fig. 1, of the reciprocating dies; and Figs. 6 and 7 illustrate the product of the machine.

Like letters of reference indicate like parts in each.

Our invention relates to the manufacture of double-pointed metallic blanks by means of double-beveled dies, the same being so constructed and operated that they shall be simultaneously operative in forming two points at the same time.

To enable others skilled in the art to make and use our invention, we will proceed to describe its construction and mode of operation.

In any suitable frame-work, a , we arrange the horizontally-moving ram d , and guide it in its motion back and forth by slides e e , working in grooves of the posts of the frame a . In the end of the ram d is a double-beveled die, g , having two operative faces, which recede backward from the middle vertical line, as more fully shown in Figs. 2, 3, and 4. This die is fastened to the end of the ram by a dovetail joint, but may be secured by clamps or in other convenient way.

A reciprocating motion is imparted to the ram d by means of the arm f , or in other suit-

able way, thereby causing the die g to operate against the counter-die h , which is similar in shape, having two faces receding backward from a vertical line at or near its middle part.

The die h is secured to the stationary block i , but may be mounted on a ram, like the ram d , and so arranged as to operate simultaneously therewith, so that the two dies shall come together at the end of the inner stroke of the rams.

The operation is as follows: A blank or bar of the proper shape for the body of the article to be made is placed between the two double-faced dies g h , and the ram, being operated by the lever f , forces the die g forward against the blank, thus making double bevels on two of its opposite sides. The ram is then drawn back, and the blank is turned one-quarter way around, so as to bring its other two sides between the dies at the next forward stroke of the ram. This operation is repeated until the blank is swaged to the form shown in Fig. 6, which shows two pointed blanks joined at the point-ends by a slight pin of metal.

These dies are more particularly applicable to making harrow-teeth, though also useful for other purposes. Such dies may each have but a single pair of double faces; or, if so preferred, they may have, either or both, a series of faces of different heights, suitably formed for compressing the iron at successive stages of the operation, as illustrated in Fig. 4.

The double conical taper shown in Fig. 7 has heretofore been made by a pair of reciprocating dies, c b , the converging faces of which (or one of them) work lengthwise and opposite to each other. To adapt our machine to the same end we fit up the dies g h with a groove, m , in each face of a conical form, decreasing in size or tapering toward the middle of the die, as shown in Fig. 3. The operation in such case is substantially that first described.

We do not confine ourselves to the exact

angle of bevel shown in the dies, but vary this to suit the article to be produced. Dies also made as described, and with like operation, may be arranged in hammers, presses, and rolls, so as to produce the same effect.

What we claim as our invention, and desire to secure by Letters Patent, is—

A pair of double-beveled dies suitably arranged so as, by successive impacts on the opposite sides of the rod, bar, or blank placed and rotated between them, to form the poly-

onal or conical points of two blanks at the one operation, substantially as described.

In testimony whereof we, the said JOHN PEDDER and GEORGE ABEL, have hereunto set our hands.

JOHN PEDDER.
GEO. ABEL.
